UNITED STATES PATENT OFFICE.

ALEXANDER MALM, OF NEW YORK, N. Y., ASSIGNOR TO T. W. & C. B. SHERIDAN, OF SAME PLACE.

MACHINE FOR BACKING BOOKS.

SPECIFICATION forming part of Letters Patent No. 427,434, dated May 6, 1890.

Application filed November 21, 1889. Serial No. 331,144. (No model.)

To all whom it may concern:

Be it known that I, ALEXANDER MALM, a citizen of the United States, residing at New York, in the county and State of New York, have invented new and useful Improvements 5 in Machines for Backing Books, of which the following is a specification.

This invention relates to machines for backing books; and it consists in certain novel 10 features and combinations, hereinafter described, reference being had to the accompanying drawings, in which—

Figure 1 is a front elevation, partly in section, of a book-backing machine containing 15 the invention. Fig. 2 is an elevation of a section taken on the line $x x$ of Fig. 1. Fig. 3 is a plan view. Fig. 4 is an elevation of a section taken on the line $x x$ of Fig. 1 when both foot-levers are down. Fig. 5 is a separate view showing, among other things, the jaws and the rods by which they are opened and closed.

The letter A designates the frame of the machine, and B C are jaws for gripping and 25 holding the books to be backed. These jaws are mounted on a common axis or rod D, on which they are free to swing to and fro to receive the work. The ends of the axis D are journaled and supported in sliding boxes E, placed in openings in the ends of the frame, the boxes being prevented from falling 30 out of the frame by flanges F F, formed on the outer and inner sides of the boxes, and which overlap the edges of the opening. The flanges are indicated by dotted lines in Figs. 35 1, 2, and 4. The boxes are supported and adjusted in the frame by means of an adjusting-slide G, on which the boxes rest, and which extends through the frame of the machine 40 from side to side. The ends of the slide are wedge-shaped on their under surfaces and rest on blocks H H, which are supported on stiff springs I I in the same openings in which the boxes are placed.

45 The boxes are raised and lowered in the frame by moving the slide G endwise, which is done by means of the adjusting-screw J, which passes loosely through a lug K, formed on one end of the slide outside of the frame, 50 which lug comes between the hand-wheel L of the screw and a fixed collar M. The screw

passes through a tapped hole made for it in the adjacent box E, and consequently when the screw is turned in one or the other direction the slide is moved in the corresponding 55 direction upon and over the blocks H H, and the boxes are thereby either raised or lowered. The blocks H H rest on the springs I, which serve to counteract any excessive pressure on the jaws in working the forming-roller 60 over the book.

The forming-roller N is adjustably mounted in a frame that extends across the upper part of the machine, and is of greater length than the jaws. The upper ends of the frame the 65 connected to each other by rods P P, and the lower ends are connected by pins P' P' to separate bell-crank levers Q Q, which turn on pins R R, Fig. 3, and whose longer arms S S are pivoted to the upper ends of connecting- 70 rods T T, whose lower ends are pivoted to the inner arms of bell-crank levers U U, whose axis V extends from one side to the other of the frame of the machine, the other arms of said bell-crank levers being pivoted to the 75 link W, which is pivoted to the foot-lever X.

The journals of the forming-roller N are mounted in sliding boxes Z Z in suitable openings in the roller-frame, said boxes being 80 adjusted by means of screws 1 1 in the ordinary manner, as indicated in Figs. 1, 2, and 4.

When the forming-roller is out of action and the foot-lever X and connections are in the position shown in Fig. 2, the roller-frame is thrown down upon the rest 3. When the 85 roller-frame is raised ready for action, as in Fig. 4, it is oscillated on the pins P' P' by the hands of the workman, who grasps the sides of the frame or the connecting-rods P and rolls the forming-roller N to and fro in contact with the back of the book which is clamped between the jaws.

The jaws B C are opened and closed by means of connecting-rods extending to them from a shaft 4, as follows: The shaft 4 is formed 95 with an eccentric or cam 5, (see Figs. 2 and 4,) to which are connected the connecting-rods 6 7, of which rod 6 is extended to the inner jaw C and rod 7 is extended to the outer jaw B, to which jaws the rods are attached respectively by pins, as indicated in Figs. 2 and 4. The cam-shaft 4 is provided at one end with

a rigidly-attached worm-gear 8, with which engages a worm 8^a on a rotating shaft 8^b, provided with a handle 9 in the form of a hand-wheel, so that by turning the latter the worm 5 and worm-gear rotate the cam-shaft, and thereby open or close the gripping-jaws.

It will be observed by looking at Fig. 4 that by turning the eccentric 5 in the direction of arrow 1, marked near it in said figure, the 10 jaws C and B will be moved away from each other, and that by turning the same in the opposite direction the jaws will be moved toward each other.

The connecting-rod 6 is made in two sections, (see Fig. 3,) so as to form a toggle-lever, said sections being joined by a pivot 10, to which is attached the connecting-rod 11, which extends to the foot-lever 12. The foot of the connecting-rod 11 is pivoted at 18 to the shorter 20 end of the segmental lever 13, which is pivoted by a pin 14 to the foot-lever 12, the longer end of said segmental lever 13 being provided with teeth which are in engagement with teeth on a stationary rack-bar 15, which 25 in this example is fast on the axis V of the bell-crank levers U. The connecting-rod 11 is in two parts, which are united by a right and left hand nut 16, so that the rod can be shortened or lengthened at pleasure.

30 When the jaws are ready to receive the work, the longer arm of foot-lever 12 is up, and it is held up by the weight 17 on the shorter end of said foot-lever, the joint 10 of toggle-lever 6 being meanwhile bent upward, 35 as illustrated in Fig. 5, so that full pressure is not yet made against the jaw. When the book to be rounded is in place in the jaws, the foot-lever 12 is brought down to its full extent, (see Fig. 2,) carrying down with it the 40 segmental lever 13 and rod 11, the segmental lever as its teeth pass over the teeth of the rack-bar 15 being turned on the pivot-pin 14, so as to throw the shorter end of the segmental lever downward, thereby causing a 45 downward pull on rod 11 and on the jointed rod 6, so as to straighten that rod and give an additional thrust against the jaw C, thereby compressing the book between the jaws. It will be observed that this additional pressure 50 on the jaw C is not accompanied by and does not produce any change in the position of the jaw B, nor of the connecting-rod 7, nor of the eccentric on shaft 4. Instead of employing a cam, as shown, on the shaft in connection with the rods 6 7, I can make the eccentric connection by means of lugs on opposite sides of the shaft and connect said rods 6 and 7 therewith, so as to obtain the motion desired.

60 When the book is properly held and secured between the jaws, the foot-lever X is brought down, whereby through the agency of the link W, bell-crank levers U, connecting-rods T T, and bell-crank levers Q Q the roller-frame is swung to its working position, (see Fig. 4,) the forming-roller N being in proper position to be operated upon the back of the

book. The bell-crank levers Q Q are seen in the plan view, Fig. 3, and the longer arm S of one of them is seen in Fig. 4, where its end 70 is connected to one of the connecting-rods T. The pins on which the said crank-levers Q turn are in Fig. 4 hid by the jaw C; but the hidden portions are indicated by dotted lines.

The foot-levers X and 12 are provided with 75 catches, which fasten them down automatically when they have been brought down by the operator to their lowest position. One of them is shown in Figs. 2 and 4—namely, the one that acts on foot-lever 12—that which 80 appertains to the other foot-lever X being hid in Fig. 4 behind foot-lever 12. The catches are constructed as follows, namely: On the under surface of the foot-lever near its end is formed a keeper or socket 19, which 85 is adapted to receive the free end of a bolt 20, whose other end is pivoted to the upright arm 21 of a weighted foot-lever 22, which is pivoted at 23 to the lower part of the frame of the machine. The free end of bolt 20 is beveled on its upper side, so that when the foot-lever 12 is pushed down the adjacent lower edge of the keeper 19 strikes the beveled edge of the bolt 20 and causes the lever 22 to be turned on its pivot against its weighted end, 90 so as to withdraw the bolt a little distance and allow the keeper to pass the end of the bolt, which then, through the action of the weight, passes into the keeper 19 and locks said foot-lever. The outer end of lever 22 is provided with a foot-piece 24 to enable the workman to withdraw the bolt 20 from the keeper by turning the lever 22 on its pivot 23. The bolt 20 is supported when out of the keeper by the foot of the frame A through an opening in which it slides. A similar catch or locking device is applied to foot-lever X. By thus locking the foot-levers X and 12 in their lower positions the workman is relieved from giving them attention after the book is secured in the clamping-jaws until it becomes necessary to remove the book and supply the jaws with fresh work.

What I claim as new, and desire to secure by Letters Patent, is—

115

1. In a book-backing machine, the combination, with the swinging gripping-jaws, of a rock-shaft having a worm-gear, rods eccentrically connected to the rock-shaft and secured, respectively, to the gripping-jaws, and a rotating shaft having a worm engaging the worm-gear for rocking the rock-shaft, substantially as described.

2. In a book-backing machine, the combination, with the swinging gripping-jaws, of a 125 rock-shaft having a worm-gear, a rod eccentrically connecting one jaw with the rock-shaft, a toggle-lever eccentrically connecting the other jaw with the rock-shaft, a rotating shaft having a worm engaging the worm-gear 130 on the rock-shaft, and a foot-lever connected with the toggle-lever, substantially as described.

3. In a book-backing machine, the combina-

tion, with the swinging gripping-jaws, of a rock-shaft, a rod eccentrically connecting one jaw with the rock-shaft, a toggle-lever eccentrically connecting the other jaw with the rock-shaft, a weighted foot-lever, a toothed segment pivoted to the foot-lever, a stationary rack with which the toothed segment engages, and a rod-connection between the toothed segment and the toggle-lever, substantially as described.

4. In a book-backing machine, the combination, with the gripping-jaws, the swinging frame carrying the forming-roller, the foot-levers, each having a keeper or socket on its under side, and connecting devices between

the foot-levers, the swinging frame, and one of the jaws, of an automatic locking-catch for each foot-lever, composed of a weighted lever pivoted to swing in a vertical plane and carrying a sliding bolt on its upper side to engage the keeper or socket on the under side of the foot-lever, substantially as described.

In testimony whereof I have hereunto set my hand in the presence of two subscribing witnesses.

ALEXANDER MALM.
